UNITED STATES PATENT OFFICE.

JOSEPH LUDWIG STEINGÄSSER, OF MOMBACH, NEAR MAINZ, GERMANY.

UNIVERSALLY-EXTENSIBLE TOOL-SHAFT.

No. 899,082.

Specification of Letters Patent. Patented Sept. 22, 1908.

Application filed November 5, 1907. Serial No. 400,765.

To all whom it may concern:

Be it known that I, JOSEPH LUDWIG STEINGÄSSER, a subject of the German Emperor, and resident of Mombach, near Mainz, 5 Germany, have invented certain new and useful Improvements in Universally-Extensible Tool-Shafts, of which the following is a specification.

The object of my present invention relates 10 to an extensibly mounted driving shaft for stripping-machines, grinding-machines, and polishing-machines for wood at the lower end of which the tool is removably fastened.

In the accompanying drawing in which I 15 have illustrated my invention like letters of reference refer to like parts throughout the different views.

In said drawing, Figure 1 shows a vertical 20 longitudinal section along the shaft. Fig. 2 shows a cross section on lines I—I of Fig. 1.

The shaft consists of the outer pipe casing 25 a on the upper end of which a driving disk b is fastened. The lower end carries a threaded piece c. Screwed unto said piece c is a coupling box d into which a shorter pipe e is 30 soldered, said pipe being provided with longitudinal slots f. I also provide an inner pipe g serving as receptacle for the polishing substance. The upper end of the pipe g 35 carries the filling pot h while its lower end is provided with a ball i. The member k is provided with a conduit coacting with a conduit l, the outer end of the former being provided with a tube m. A cock n regulates the 40 feeding of the polishing substance towards the tool. Below the coupling box d I provide on the pipe g a handle o, provided with ball bearings p and rotatable around the pipe g. Mounted on the pipe g inside tube a 45 is besides the ordinary guide q a catch s having noses r. Between said catch and the box d I provide a spring bearing u between two ball rings t. The tool clamp k having the ball i consists of a two parted casing providing the catch pins v moving in slots of the ball i and the fastening pins w for the tool provided with a bayonet lock. By means of an adjusting nut x the bayonet lock is secured after the mounting of the tool.

The operation of the shaft is as follows: 50 At first the outer pipe casing a is quickly rotated by the disk b by means of a rope or the like, while the inner pipe g is still in rest. After the tool has been fastened to the casing k I draw the handle o downward whereby 55 the spring u is pressed together by the catch s fixed to the pipe g and the noses r of the ring s are simultaneously guided by means of the sloping surfaces of the pipe e into the slots f so forcing the pipe g and consequently 60 the tool to rotate with the pipe a. The handle o serves not only to operate the pipe g but also to effect a translatory motion of the shaft a, said shaft being slidably mounted in a spherical sleeve z which is mounted for 65 universal rotation in the frame member y. By means of this arrangement I can complete any longitudinal or transversal motion of the tool over the working table. If I release the handle o the noses of the catch s are 70 pressed out from the grooves f of the pipe e by springs u, whereby the pipe g is arrested; I can now exchange the tools without stopping the whole machine.

What I claim as new and desire to secure 75 by a United States Letters Patent, is:—

In a telescopic tool shaft, the combination 80 of an outer pipe, an inner pipe and a medial pipe rotatable with said outer pipe and provided with grooves, a handle mounted on the inner pipe, a tool clamp on said pipe, a filling pot on said pipe, a ring on said pipe, keys on said ring, adapted to engage with grooves of the medial pipe, an extensor spring actuating said ring and a ball sleeve mounted on 85 the outer pipe said sleeve being rotatably mounted in a frame member, substantially as described and for the purpose set forth.

In testimony whereof I have hereunto signed my name this 8th day of October 90 1907, in the presence of two subscribing witnesses.

JOSEPH LUDWIG STEINGÄSSER.
